UNITED STATES PATENT OFFICE

2,178,750

CENTRIFUGAL DRIER

Claude M. Garland, Chicago, Ill.

Application March 17, 1938, Serial No. 196,334

4 Claims. (Cl. 34—10)

My invention relates to apparatus for removing moisture from granular material such as coal, sand, gravel and the like, in which the moisture is removed by rotating the mass of material at high speed so that any surface moisture is thrown out by centrifugal force. My improvement in this type of equipment consists in admitting hot gases to this equipment and causing the hot gases to pass through the material as it rotates and passes through the drier. These gases, in passing through the material, entrain a certain amount of moisture and carry this out in mechanical suspension, thereby assisting the centrifugal action, and in addition to this, the heat in the gases evaporates a portion of the moisture in the material. The object of my invention is therefore to improve the drying performance of centrifugal drying equipment by passing hot gases through the material in its passage through the drier.

Referring to the drawing, in which like numerals refer to like parts, Figure I is a section through my improved centrifugal drier. This drier comprises a shell 1, closed at the top by a cover plate 11. On the cover plate 11 is mounted an outlet for hot gases 12, and an inlet 52 for the admission of the material to be dried. To the inlet 52 communicates a pipe 31 to which is attached a screw conveyor 6. This screw conveyor comprises the screw 9, mounted on the shaft 29, which is in turn mounted in the bearings 8 and 43. To the end of the shaft 29 is rigidly attached a sprocket 10, which may be driven by a chain from any convenient source of power. On the casting 52 is provided a bearing 44 in which is mounted a shaft 21. The lower end of the shaft 21 is mounted in a bearing 5, which is supported by arms 4, mounted in the shell 2, which is in turn bolted to the shell 1 at 45. On the shaft 21 and rigidly attached thereto by means of the keys 20, hubs 18 and 22, and the arms 25 and 19, is mounted a cone 26, which is adapted to rotate with the shaft. This cone 26 is made up of horizontal ribs 16, and vertical ribs 13. The open spaces 14 are covered over by perforated plates or screens 17. On the shaft 21 is also rigidly mounted a distributor plate 24 on which are located ribs 43, usually four in number. In the shell 2 is located a drip pipe 23 for discharging any water that may accumulate. To the shell 2 is bolted at 46 the shell 3, which is provided with a conical bottom 47. In the shell 3 is mounted the truncated cone 37, and the diaphragm 36, which form, with the sides of the shell 3, an annular space of triangular section. To the annular space communicates the elbow 35,

the pipe 34, which in turn communicates with the pipe 27. The pipe 27 extends through the conical bottom 47 of the shell 3, and has an exit 30 adapted to discharge gases to the cone 33, provided with perforations 39 in the side wall. The 5 perforations 39 are about one-eighth of an inch wide and about four inches long. In the bottom of the cone 47 is located the paddle wheel 41, mounted on the shaft 49, which is in turn supported in the side walls of the material discharge 10 outlet 42, which is of rectangular section. On the shaft 41 is mounted a pulley 40, which is adapted to be driven by any convenient source of power:

The pipe 27 is attached to the bottom cone 47 15 at 50, and forms a support for the cone 33.

The operation of my device is as follows:

The material to be dried is discharged to the magazine or hopper 7, and the screw 9 is rotated by means of a sprocket attached to the shaft 29, 20 which is driven by a chain from any convenient source of power. As the screw 9 rotates, the material to be dried passes down through the pipe 31, between the arms 25, and onto the spreader 24. The shaft 21, the cone 26, and the spreader 24, are 25 rotated by means of a belt applied to the wheel 28. As the cone 26, and the spreader 24, rotate, the centrifugal force throws the material from the spreader 24 onto the inner surface of the cone 26, which consists of screens 17. Due to centrifugal 30 action the material passing off the spreader 24 onto the cone 26, gradually descends along the surface of the cone and the water contained in the material, due to the centrifugal force, passes out through the perforations in the screens 17. As 35 the material leaves the screens 17, and the rotating cone 26, the material drops onto the inverted truncated cone 37, descends the side walls of this truncated cone by gravity, and is discharged onto the cone 33, and from the cone 33 40 discharges into the inverted cone 47, forming the bottom of the shell 3.

As the material is descending through the drier, hot gases enter through the pipe 27, pass upward through the pipe 34, and enter at 35 the annular 45 compartment 48. At the same time another portion of the gases entering through the pipe 27 passes up through the pipe 30 and out through the perforations 39 in the cone 33. At the same time the gases entering the compartment 48, pass 50 through the perforations 38 in the inverted truncated cone 37 and the material passing there-over. The gases passing upward from the cone 33 and the truncated cone 37 enter the bottom of the cone 26, pass through the material de- 55

scending over the screens 17, through the screens 17, and out through the pipe 12. The hot gases may be obtained from any convenient source and will range in temperature between 400 and 1000 5 degrees F. As they pass through the material on the screens 17 they pick up moisture by entrainment and at the same time reduce the moisture by evaporation. Any dust picked up by the gases in the lower part of the drier is scrubbed out by 10 the wet material passing over the screens 17, as the gases pass out.

While I have shown only one inverted truncated cone 37, and one cone 33, which form a pair, as many of these pairs of units may be installed as is 15 necessary to obtain the proper degree of dryness. This may result in the use of one pair, or possibly five or six pairs.

During the operation of the equipment the material passing through the screw conveyor 6 forms 20 a seal to prevent the escape of hot gases which pass out through the opening 12. Likewise, the paddle wheel 41, rotating by means of a belt on the wheel 40, retards the discharge of material from the cone 47, thereby sealing off the cone 47 25 and preventing the escape of gases at this point. The fuel charging device at the top consisting of a screw conveyor 6, may also be used as a discharging device at the bottom of the drier. At 23 is provided a drip connection for any accumulated 30 water, which consists of a pipe communicating with the shell 1, and sealed in water to prevent the escape of hot gases by means of the seal 51.

It will be seen from the above description that 35 I have provided means for greatly increasing the efficiency of centrifugal drying equipment. While the parts shown and described are the preferred arrangement of my equipment, it should be understood that my invention is not limited to the precise construction set forth, but contains within 40 its purview such changes as may be made within the scope of the appended claims.

What I claim and desire to secure by Letters Patent is:

1. In a centrifugal drier of the type described, 45 a shell, a material charging device mounted near the top of the said shell and adapted to supply material thereto, a material discharging device located near the bottom of the said shell and adapted to discharge material therefrom, a shaft 50 vertically mounted within the said shell and adapted to rotate therein, a distributing device 24 mounted on the said shaft adapted to receive material discharged from the said material discharging device, a truncated conical member supported from the said shaft and adapted to receive on its 55 inner sides material from the said distributing device, means for rotating the said shaft, the said distributing device and the said truncated conical member whereby materials charged to the shell 60 by means of the said material charging device is distributed from the said distributing member onto the inner surface of the said truncated conical member, an inverted truncated perforate cone beneath the said truncated conical device, means 65 for discharging gases through the perforations in the said inverted truncated cone, and a gas outlet near the top of the said shell.

2. In a centrifugal drier of the type described, 70 the combination of a shell, a material charging device mounted near the top of the said shell and adapted to supply material thereto, a material discharging device located near the bottom of the said shell and adapted to discharge material therefrom, a shaft vertically mounted within the

said shell and adapted to rotate therein, a distributing device 24 mounted on the said shaft adapted to receive material discharged from the said material discharging device, a truncated conical member supported from the said shaft and adapted to receive on its inner sides material from the said distributing device and the said truncated conical member mounted thereon whereby material charged to the shell by means of the said material charging device is distributed from the said distributing member onto the inner surface of the said truncated conical member, an inverted truncated perforate cone beneath the said truncated conical device, means for discharging gases through the perforations in the said inverted truncated cone, a perforate cone beneath the said inverted truncated cone, means for discharging gases through the perforations in the said perforate cone, and a gas outlet near the top of the said shell.

3. In a centrifugal drier of the type described, a shell, a material charging device mounted near the top of the said shell and adapted to supply material thereto, a material discharging device located near the bottom of the said shell and adapted to discharge material therefrom, a shaft vertically mounted within the said shell and adapted to rotate therein, a distributing device 24 mounted on the said shaft adapted to receive material discharged from the said material discharging device, a truncated conical member supported from the said shaft and adapted to receive on its inner sides material from the said distributing device, means for rotating the said shaft, the said distributing device and the said truncated 35 conical member whereby material charged to the shell by means of the material charging device is distributed from the said distributing member onto the inner surface of the said truncated conical member, an inverted truncated perforate cone beneath the said truncated conical device, means for discharging gases through the perforations in the said inverted truncated cone, a perforate cone mounted beneath the said inverted truncated cone, means for discharging gases through the perforations in the said perforate cone, a gas outlet near the top of the said shell, and an offset for the accumulation of water in the said shell.

4. In centrifugal apparatus of the type described, the combination of a shell, a gas outlet 50 on the top of the said shell, a material charging device having communication with the top of the said shell, a material discharging device communicating with the bottom of the said shell, a shaft vertically mounted in the axis of the said shell, a hollow truncated conical member attached to the said shaft and adapted to rotate therewith, perforations in the side of the said conical member, a distributing plate beneath the top of the said conical member mounted on the said shaft and adapted to receive material from the said material charging device and distributing same to the inner surface of the said conical member, a perforated inverted truncated cone beneath the said conical member, a perforated cone beneath the said truncated cone, a gas pipe for supplying hot gases to the underside of the said perforated cone, a branch gas line adapted to deliver hot gases beneath the said inverted truncated cone, an offset in the said shell, and a sealed drain connection 60 communicating with the said offset, substantially as described.

CLAUDE M. GARLAND.
